UNITED STATES PATENT OFFICE

2,516,767

ABUTMENT CONSTRUCTION FOR TUBES

Matthew P. Graham, Detroit, Mich., assignor to
 Thompson Products, Inc., Cleveland, Ohio, a
 corporation of Ohio

Application April 30, 1947, Serial No. 744,811

6 Claims. (Cl. 287—90)

1

This invention relates to an abutment construction for tubes and the method of producing the same.

Specifically the invention deals with an abutment construction comprising a C-shaped or slotted ring telescoped in a tube and having the tube deformed into the slot or gap as well as into the body of the ring to form a longitudinally and rotatably locked abutment in the tube.

The invention will hereinafter be specifically described as embodied in a tie rod joint, but it should be understood that the principles of this invention are broadly applicable to abutments or bottoms for tubes in general.

According to the present invention, a cleft sleeve member or bottoming ring having a gap or notch therein is inserted in a tube or housing and the tube or housing is then deformed as by spinning, swedging, or the like to form nested anchoring beads holding the ring against longitudinal movement relative to the tube and to flow a rib-like portion of the tube into the gap of the ring to prevent rotation of the ring in the tube. The tube metal flowed into the gap and the friction grip of the tube bead anchors the ring sufficiently so that a reamer can act on an end face of the ring to create an abutment shoulder at the exact desired position in the tube.

Furthermore, during the swedging or beading operation, the split ring will spring inwardly by an amount greater than the tube is set and its tendency, therefore, is to expand after the deforming operation, resulting in greater tightness within the tube.

A feature of the invention, therefore, is the provision of an abutment construction including a tubular member having a gap therein into which a portion of a tubular housing may be flowed for retaining the member against rotation.

Another feature of the invention resides in the utilization of a single flat strip to form economically a generally C-shaped bottoming member.

A further feature of the invention is the provision of a C-shaped bottoming member having recesses in the opposed ends thereof for locking the member against rotating and longitudinal movements in a tubular housing.

An object of the invention is to provide an inexpensive bottoming ring which may be easily locked in a tube and reamed without causing rotation thereof.

A further object of the invention is to provide an abutment construction which is readily and securely positioned within a tubular housing and is prevented from rotating therein.

Another object of the invention is to provide an abutment construction including a tubular member which may be inserted to a controlled distance within the end of a tube and then reamed to the exact dimension required to provide a smooth annular shoulder for tie rod assemblies and the like.

A specific object of the invention is to provide a C-shaped bottoming ring which may be inserted to a controlled distance within the end of a tube and the tube tightly formed thereover, whereby the tube flows into the gap in the C-ring and the ring is held against both rotation and translation, the ring being sprung inwardly by an amount greater than the tube is set during the tube forming operation and subsequently tending to expand increasing its tightness within the tube.

Other and further objects of the invention will be apparent to those skilled in the art from the following detailed description of the annexed sheet of drawings which, by way of preferred example only, illustrate one embodiment of the invention.

25 On the drawings:

Figure 1 is a fragmentary side elevational view of a tubular housing for a tie rod assembly including an abutment construction according to this invention;

Figure 2 is an enlarged fragmentary longitudinal sectional view taken substantially on the line II—II of Figure 1 with parts partially in elevation;

Figure 3 is an isometric view of a C-shaped bottoming ring according to this invention;

Figure 4 is a fragmentary longitudinal sectional view showing the C-ring of Figure 3 inserted within a tubular housing prior to the forming operation thereof;

Figure 5 is a transverse sectional view taken substantially along the line V—V of Figure 2;

Figure 6 is a fragmentary longitudinal sectional view taken substantially along the line VI—VI of Figure 5;

Figure 7 is an isometric view of an alternate embodiment of my invention; and

Figure 8 is a fragmentary longitudinal sectional view similar to Figure 2 but showing the alternate embodiment of my invention.

50 As shown on the drawings:

My invention will be described as to its physical structure; it is believed that the method of producing my abutment construction will be sufficiently clear therefrom so that specific reference to the method will be unnecessary.

In Figures 1 and 2, the reference numeral 10 designates a tubular tie rod housing having an internally threaded end 10a and a cylindrical opening 10b in the peripheral portion of the housing adjacent the threaded end 10a.

The housing is adapted to receive a tie rod assembly 11 composed of a pair of opposed bearing blocks 12 and 13, a helical spring 14 abutting the block 12 adjacent the threaded end 10a, a closure plug 15 threading into the end 10a against the spring 14 and a ball stud 16 having a ball end 16a projecting into said opening 10b and riding on the inner opposed semi-spherical dished portion 12a and 13a of the bearing blocks 12 and 13.

The bearing blocks 12 and 13 have cylindrical body portions 12b and 13b fitting snugly into said tubular housing 12 with flat outer surfaces 12c and 13c, the surface 12c abutting the spring 14 for maintenance of a tight bearing relation between the bearing blocks and the ball end of the stud.

Anchoring the tie rod assembly 11 at any desired distance within the tubular housing 10 in cooperation with the closure plug 15 and spring 14 is the abutment construction 17 of my invention. The abutment construction comprises a short tubular member or bottoming ring 18 shown in Figure 3 preferably formed economically from a flat strip and providing a longitudinal notch or gap 18a between the spaced opposed ends 18b and 18c thereof.

In manufacturing the tie rod socket, the bottoming ring 18 is inserted to a controlled distance in the end of the housing 10 as shown in Figure 4. The tube 10 is then formed tightly by spinning or swedging over the short bottom ring 18 as indicated at 10c, thus deforming the tube and the ring 18 to produce a peripheral groove 18d as shown in Figures 2 and 6. In this operation, the metal of the tube or housing 10 indicated by reference numeral 10d will flow into the notch 18a as shown in Figures 4 and 5, thus locating the bottoming ring and preventing its rotation under the action of a reamer. Because of this gap, therefore, the ring will maintain its tightness within the tube, while the presence of a portion of the housing in the groove 18d prevents displacement of the ring.

During the swedging or beading operation, the bottom ring will spring inward by an amount greater than the tube is set. Its tendency, therefore, is to expand after the deforming operation, resulting in great tightness within the tube.

In assembling the tie rod joint, after the opening 10b has been formed and the tube end threaded at 10a, the annular surface 18e of the bottoming ring 18 is reamed to provide a smooth flat seating surface at the proper distance from the opening 10b. The bearing block 13 is then inserted into the tube, the outer surface 13c thereof abutting the annular reamed surface 18e. The ball end 16a of the ball stud 16 is next inserted through the opening 10b and into engagement with the dished portion 13a of the bearing block 13. The other bearing block 12 is inserted in the tube to engage the ball end 16a at its dished portion 12a, the helical spring 14 is inserted and the closure plug 16 is then threaded on the end 10a of the tube compressing the spring which in turn urges the bearing block into engagement with the ball end of the stud 16.

As an alternative embodiment of my invention a bottoming ring such as designated by the reference numeral 19 and shown in Figure 7 may be employed. The bottoming ring is sub-

stantially the same as the ring 18 with the exception that the opposed ends 19a and 19b have opposed recesses 19c and 19d therein providing a longitudinal gap 19e having an enlarged central portion 19f.

The resulting abutment construction after the same manufacturing process as for the ring 18 is similar except that the metal of the tube 20 flows into the recesses 19c and 19d as well as the other parts of the gap 19e. The sides of the recesses 19c and 19d thus serve as a further reinforcing lock against longitudinal displacement as well as providing added tube metal resisting rotation, while providing the same annular seating area to the bearing block 13.

Reference numeral 20a represents the annular constructed portion of the tube and 19g the corresponding annular groove in bottoming ring 20.

From the above description it will be understood that the invention now provides an abutment construction for tubular housings such as used with a tie rod assembly which is capable of being reamed without loosening rotation to provide a smooth flat surface abutment for seating bearing blocks of tie rod assemblies and the like. The abutment construction includes a C-shaped member economically formed of a single flat strip.

It will, of course, be understood that various details of construction may be varied through a wide range without departing from the principles of this invention and it is, therefore, not the purpose to limit the patent granted hereon otherwise than necessitated by the scope of the appended claims.

I claim as my invention:

1. In a tie rod joint comprising a tube housing for receiving a tie rod assembly, a tubular member having a central peripheral groove therearound and a gap therein, the housing formed into said groove and gap to prevent rotation and translation of said members with respect to the housing.

2. In a tie rod joint comprising a tubular housing for receiving a tie rod assembly, a generally C-shaped bottoming ring having recesses in the spaced opposed ends thereof, the housing flowed into said recesses and between the spaced opposed ends of said bottoming ring.

3. In a tie rod joint comprising a tubular housing for receiving a tie rod assembly, a generally C-shaped tubular member having a recess in at least one of the spaced opposed ends thereof and said member having an annular depression in the periphery thereof, the housing flowed into said depression, recess and between said spaced ends.

4. A housing assembly comprising a tubular body, a cleft sleeve in the body, nested embossments on the body and sleeve holding the sleeve and body in fixed longitudinal relation, and a rib on the body projecting into the cleft gap of the sleeve to hold the sleeve and body in fixed rotative relation.

5. A housing for joints and the like comprising a tube, a cleft ring in said tube, an internal rib on said tube projecting into the cleft gap of the ring for holding the ring against rotation, and an inwardly extending annular bead on said tube nested into said ring for holding the ring against longitudinal movement in the tube.

6. In a tie rod assembly including a tubular housing for receiving a ball stud with a ball end riding in opposed bearing blocks, a tubular member having a flat annular surface abutting one bearing block, said member having a longitudinal gap therein and an annular constriction there-

around, and said housing at least partially filling said gap and constriction, whereby said member is held against rotation and translation in said housing.
